SHAFT END MOUNTING FOR SEALING AND LOOP FORMING A PUMP DIAPHRAGM

James L. Edelen, Kirkwood, Mo., assignor, by mesne assignments, to ACF Industries, Incorporated, New York, N.Y., a corporation of New Jersey

Application May 12, 1954, Serial No. 429,343

3 Claims. (Cl. 29—156.4)

This invention relates to diaphragm type of pumps and, more specifically, to a sub-assembly used in such pumps, including a mounting stem, diaphragm, and retainer.

It is well understood that in pumps of this kind service life depends in good measure upon the proper mounting of the diaphragm in the pump, and this, in turn, depends upon the right amount of initial loop provided and proper pressure of the backing plates on the diaphragm to prevent any leakage between the diaphragm and the stem. This pressure, however, should be limited to avoid any stresses which might contribute to premature failure of the diaphragm. It is therefore desirable that the pressure between the backing plates during the assembly be carefully controlled.

Heretofore it has been common practice to assemble the backing plates and diaphragm on the stem of the pump by a spinning or forging operation to head-over the end of the stem into engagement with the uppermost of the backing plates. In this operation, the final sealing pressure obtained between the backing plates and the diaphragm will depend upon initial dimensions of the assembled parts as much as on the accuracy with which the spinning or forging operation is performed. In quantity production this sealing pressure cannot be accurately controlled.

This invention is aimed at obtaining more uniform pressure between the backing plates during assembly of the stem to the diaphragm and plates. It is also the object of the invention to preset the desired amount of loop in the portion of the diaphragm externally of the backing plates and simultaneously with the assembly operation of the stem with the diaphragm and plates. This avoids any strain due to the action of the pump except that imposed by the pressure of the fluid and at the same time makes unnecessary the assembly step of presetting the loop.

According to this invention, the stem for the pump is provided with the usual reduced section for receiving the backing plates and diaphragm, whereby a substantial supporting shoulder is formed. The backing plates, however, are themselves modified from usual construction to provide oppositely facing, concave surfaces. In order to provide uniform pressure between the backing plates and the diaphragm, a novel keeper washer is forced into locked engagement with a tapered groove formed in the reduced end portion of the stem. This keeper washer is produced by deforming a flat washer into a conical shape. To assemble the washer in securing relation with the groove in the stem, pressure is applied at the outer rim of the conical washer sufficient to exceed the yield point of the metal. As the washer begins to flatten under the pressure, the outer peripheral edge of its aperture grips with the taper of the groove on the stem. This requires a force of given amount, depending, of course, upon the dimensions and material of the washer. These variables can be chosen to assure the desired amount of sealing pressure necessary. It has been found

2

that this force is relatively uniform once these variables are determined. After the gripping action takes place, the force necessary to flatten the washer diminishes rapidly, and a rocking action radially of the washer takes place acting as a lever against the upper backing plate.

When the force required again approaches the pressure at the yield point of the metal, the operation is discontinued.

The results achieved so far with this method using 10 the described structure have produced uniform pressure and a stretching action on the diaphragm sufficient to provide the performed amount of loop desired.

In the drawings:

Fig. 1 is an environmental view of one type of dia-

phragm pump;

Fig. 2 is an exploded view illustrating the arrangement of the parts for assembly with the stem;

Fig. 3 illustrates the position of the parts in the initial stages of assembly; and

20 Fig. 4 illustrates the relation of the parts when finally assembled.

Referring to Fig. 1, a body casting 1 contains a pump lever housing 2 provided with a flange 3 for attachment to the engine. A pump operating lever 4 having a slideable 25 shoe 5 is pivoted at 6 within the housing 2. Pump lever 4 operates a pair of diaphragm pumps generally indicated as 10 and 11. These pumps are of the type shown in the patent to Hollembaek et al., No. 2,623,351, December 30, 1952.

30 The pump 11 has a valve casing 13 containing an inlet connection 14 and an outlet connection 15. The inlet connection 14 connects with a pump chamber 16 by way of a passage 17 controlled by an inlet check valve 18. Discharge from the pump chamber 16 is controlled by an 35 outlet check valve 19 in the outlet passage 20.

Within the pump chamber 16 is a diaphragm assembly generally indicated as 25, which includes a reciprocal stem 26 operated from the pump arm 4 in one direction and the compression spring 27 in the opposite direction.

40 The stem is secured to a diaphragm 30, which is, in turn, clamped at its peripheral edge between the pump body casing 1 and the valve casing 13. Any suitable securing means may be used to attach these parts together.

45 The present invention is concerned with the novel features and method of manufacturing the sub-assembly 25.

50 In order to illustrate the details of this sub-assembly, the drawings show an exploded view in Fig. 2 with the parts arranged in the manner to be assembled upon the stem 26. Turning to this figure, the stem 26 is illustrated as cylindrical with a reduced end portion 35 forming a supporting shoulder 36. Formed in the upper end of the reduced portion 35 is a groove 37 with a double taper.

55 The groove 37 is intentionally designed so that the widest shoulder with the gradual taper faces the shoulder 36.

The elements which are assembled on the stem 26 include a plain washer 39, a lower backing plate 40, diaphragm 30, sealing washer 41, upper backing plate 42, upper backing washer 43, and the conical keeper washer 45.

60 In the assembly of the parts above enumerated, the washers, backing plate, diaphragm, and keeper are assembled upon the stem as shown in Fig. 3. As will be noted in this figure, the backing plates are dished slightly, and it has been found that preferably this concavity should be .012 to .020 of an inch. The keeper washer 45 is a plain, flat washer pressed into conical form. The 65 sub-assembly with the parts arranged in the manner described mounted in a holder 48 are inserted in a press of any desired type which will indicate the pressure ap-

70

plied. The press member 49 is a die having a cavity 50 deep enough to receive the keeper washer 45, and is of a diameter at the bottom of the concavity the same as the original diameter of the keeper washer 45 before the coning operation. The sides 51 of the cavity 50 preferably have about a 5° taper.

In the assembly operation, as pressure is applied by the die 49 with the sub-assembly 25 suitably mounted in the holder 48 on the anvil of the press, the conical washer moves down to the groove 37 and the backing plates are flattened to tension the diaphragm. Pressure then increases until the yield point in the metal of the washer 45 is reached, thereby causing the size of the aperture in the washer to be decreased. This pressure will be sufficient to flatten the washer and cause the outer edge of its aperture to contract and grip the tapered shoulder of the groove 37. During the compression of the washer 45, the action of the backing plates to stretch the diaphragm centrally in a radial direction is completed. This forms the desired looping necessary to accommodate the stroke of the pump.

After the yield point of the washer 45 is reached, the pressure necessary to flatten the washer suddenly decreases and, as the washer flattens, it acts as a lever pivoting about the outer edge of its aperture, which is in gripping engagement with the groove. The press operation is continued until the pressure necessary to continue the flattening of the washer approaches that required at the yield point of the metal, at which point the washer appears as shown in Fig. 4 locked in final position.

The sub-assembly 25 is then complete and ready for assembly in the pump.

The small sealing washer 41 has been found to be desirable because, during the radial stretching of the diaphragm 30, the aperture receiving the stem 35 is enlarged and, without the sealing washer, a space would be left to permit leakage around the stem. The sealing washer fills this space and prevents leakage.

It has been found that the invention provides uniform results in spite of minor variations in thickness of the parts. These variations can be accommodated by the latitude provided on the shoulder 37 for receiving the keeper washer 45.

A structure has been described which will fulfill the objects of the invention above-stated, but it is contemplated that other modifications will occur to those skilled in the art which come within the spirit of the invention as defined by the appended claims.

I claim:

1. The method of clamping an assembly of two backing plates and a diaphragm therebetween against a shoulder on a pump stem, which comprises mounting a dish-shaped washer on said stem for engagement against said assembly, and applying pressure to the rim portion of the washer in a direction to flatten same while the rim portion is confined to maintain a predetermined diameter, to thereby compress the washer until it tightly engages the stem.

2. The method of clamping an assembly of two backing plates and a diaphragm therebetween against a shoulder on a pump stem, which comprises forming an annular tapered seat on said stem converging toward said shoulder, mounting a dish-shaped washer on said stem for engagement against said assembly, and applying pressure to the rim portion of the washer in a direction to flatten same while the rim portion is confined to maintain a predetermined diameter, to thereby compress the washer until it tightly engages the tapered seat on the stem.

3. A method according to claim 2, in which said two backing plates are formed dish-shaped for initial annular clamping engagement with said diaphragm adjacent their outer peripheries.
